(57) **CLAIM**

I claim the ornamental design for an transducer-protector device for medical hemodialysis lines, as shown and described.

DESCRIPTION

FIG. 1 is a perspective view from above of a transducer-protector device for medical hemodialysis lines showing the new design;

FIG. 2 is a perspective view from below thereof;

FIG. 3 is a plan view from above thereof;

FIG. 4 is a plan view from below thereof;

FIG. 5 is a front view thereof;

FIG. 6 is a rear view thereof; and,

FIG. 7 is a lateral view thereof.

The broken lines in the drawings illustrate portions of the transducer-protector device for medical hemodialysis lines and form no part of the claimed design.

1 Claim, 7 Drawing Sheets
